UNITED STATES PATENT OFFICE.

EVI W. CHRISTIE, OF SEWAREN, NEW JERSEY, ASSIGNOR TO WHEELER CONDENSER AND ENGINEERING COMPANY, OF CARTERET, NEW JERSEY, A CORPORATION OF NEW JERSEY.

SURFACE CONDENSER.

1,105,320.

Specification of Letters Patent. Patented July 28, 1914.

Application filed November 11, 1913. Serial No. 800,249.

To all whom it may concern:

Be it known that I, EVI W. CHRISTIE, a citizen of the United States, residing at Sewaren, in the county of Middlesex and State of New Jersey, have invented an Improvement in Surface Condensers, of which the following is a specification.

My present invention relates to condensers, and particularly to surface condensers, and the object thereof is primarily the provision of a surface condenser adapted for use with steam turbines having two exhaust connections, although, as will be understood, the invention is not limited to this particular use.

The condenser made in accordance with my present invention is designed to provide sufficient condensing surface for the use intended thereof, and also to eliminate extra piping and other complications incident to the employment of two separate and independent condensers for this work.

In carrying out my invention, I preferably employ a plurality of casings, each having an exhaust steam inlet, and a condensed steam outlet, a bank of tubes in each casing, a circulating liquid inlet and outlet chamber between each adjacent casing, and an equalizing chamber extending between the adjacent casings so that the vacuum in each will be the same, as will be hereinafter more particularly described.

In the drawing, Figure 1 is a central longitudinal cross section of a condenser made in accordance with my present invention, and Fig. 2 is an end elevation thereof.

Referring to the drawing, my improved condenser preferably comprises a shell or casing, indicated at 10, provided with an exhaust steam inlet 11 and a condensed steam outlet 12, and also a shell or casing 13, similarly provided with an exhaust steam inlet 14 or a condensed steam outlet 15. In the casing 10, there is a plurality of tubes arranged in banks, one of which is indicated at 16 and the other at 17. At their ends, these tubes, as is customary, are suitably connected in tube plates, 18 and 19, connected respectively to the opposite ends of the casing 10. Similarly in the casing 13 there is a plurality of tubes arranged in banks, indicated at 20 and 21. These tubes, as is also customary, are, at their ends, fixed in tube plates 22 and 23, suitably secured to the opposite ends of the casing 13.

Intermediate of the casings 10 and 13, and suitably secured thereto, I employ a circulating water box, indicated at 24. As shown, this is provided in its lower portion with an inlet 25, and at one side of its upper portion with an outlet 26. Centrally, this water box is provided with a partition 27 dividing it into inlet and outlet compartments with which the said inlet and outlet connections are in communication. At its upper portion, the water box is also provided with a partition, indicated at 28, providing an equalizing chamber 29, which, through suitable apertures in the tube plates 18 and 22, makes communication between the interior of the casings 10 and 13, so as to equalize the vacuum in these casings.

At its outer end, the casing 10 is provided with a water box 30, fitted with a cover 31, in which there may be provided suitable arm holes 32. Similarly, at its outer end, the casing 13 is provided with a water box 33, fitted with a cover 34.

In the use of the hereinbefore described condenser, the circulating water is admitted at the inlet connection 25, to the inlet chamber in the water box 24, from which it divides, a portion passing through the bank of tubes 17, in the casing 10, to the water box 30, thence through the bank of tubes 16 to the outlet chamber of the water box 24. The other part of the circulating water passes through the bank of tubes 21, in the casing 13, to the water box 33, thence through the bank of tubes 20 to the outlet chamber of the water box 24, as is indicated by the arrows shown in Fig. 1.

The exhaust steam from the turbines, or other source, is connected by suitable piping to the inlets 11 and 14, and thence comes in contact with the outer surface of the tubes in the several banks and is condensed thereon, the water of condensation being suitably conveyed from the condenser casings through the outlet connections 12 and 13.

I claim as my invention:

1. A surface condenser comprising a plurality of condenser shells in alignment and each having an exhaust steam inlet and a condensed steam outlet, a tube plate at the ends of each condenser shell, banks of tubes in each condenser shell, a water box casing placed between and secured to the adjacent tube plates of adjoining condenser shells and having inlet and outlet connections, means

- for equalizing the pressure in the condenser shells, and water box casings at the distant ends of the condenser shells.
2. A surface condenser comprising a plurality of condenser shells placed in alignment and each having an exhaust steam inlet and a condensed steam outlet, a tube plate at the ends of each condenser shell, banks of tubes secured in and extending between the tube plates of each condenser shell, a water box casing placed between and secured to the adjacent tube plates of adjoining condenser shells and having inlet and outlet connections, a partition plate in the said water box casing dividing the same into two compartments, means for equalizing the pressure in the condenser shells, and water box casings at the distant ends of the condenser shells.
3. A surface condenser comprising a pair of similar condenser shells placed in alignment and having an exhaust steam inlet and a condensed steam outlet, a tube plate at the ends of each condenser shell, tubes secured in and extending between the tube plates of each condenser shell, a water box casing placed between and secured to the adjacent tube plates of adjoining condenser shells and having inlet and outlet connections for the circulating water, a partition dividing the said water box casing into compartments for the circulating water, a second partition in one or the said compartments of the water box casing extending between the adjacent tube plates, in which ports are provided, through which ports and the chamber made in the water box casing by the second partition a communication is provided between the interior of the condenser shells, and water box casings at the distant ends of the said condenser shells.
- Signed by me this 3rd day of November, 1913.

E. W. CHRISTIE.
